Primary Examiner — Elizabeth Albert(74) Attorney, Agent, or Firm — Pamela K. Riewerts, Esq.; Larry J. Guffey, Esq.; Oliver & Grimsley, LLC(57) CLAIM

The ornamental design for a bar tool, as shown and described.

DESCRIPTION

FIG. 1 is a perspective view of a bar tool showing my new design in an upright position;

FIG. 2 is a front elevational view thereof;

FIG. 3 is a left side elevational view thereof, the right side elevational view being a mirror image of FIG. 3;

FIG. 4 is a rear elevational view thereof;

FIG. 5 is a top plan view thereof;

FIG. 6 is a bottom plan view thereof; and,

FIG. 7 is a perspective view of the bar tool in an upside-down position.

The broken lines shown in the drawings are included for the purpose of illustrating unclaimed portions and form no part of the claimed design.

1 Claim, 7 Drawing Sheets(56)
